(57) **CLAIM**

The ornamental design for a hybrid integrated circuit board, as shown and described.

DESCRIPTION

FIG. 1 is a perspective view of a hybrid integrated circuit board showing an embodiment of our new design;

FIG. 2 is a front elevational view thereof, which is symmetrical to a rear elevational view not shown herein;

FIG. 3 is a left side elevational view thereof, which is symmetrical to a right side elevational view not shown herein;

FIG. 4 is a top plan view thereof; and,

FIG. 5 is a bottom plan view thereof.
